GAS OPERATED PUMP FOR OIL WELLS
AND THE LIKE

Wilson E. Green, Eunice, N. Mex.

Application April 18, 1941, Serial No. 389,128

8 Claims. (Cl. 103—5)

This invention relates to the art of pumping oil wells and the like and particularly relates to that class of such apparatus in which gas under pressure is used for operating a pump in the well.

The common forms of pumps used for the purposes indicated are usually operated by a string of rods which extend from the pump in the well to appropriate mechanism above the ground which causes a reciprocation of the rods. Such apparatus is costly and is subject to breakage due to the stresses imposed on it during operation.

In the present invention no rods or other mechanical means are provided extending to the surface of the ground for operation of a pump but on the other hand gas or air under pressure is conducted from the surface of the ground to what may be termed a pump operating assembly or fluid motor which is closely associated with and directly connected to a common form of pump located in the well.

One of the principal objects of the present invention is to provide apparatus of the class described in which after the gas has moved the pump through its pumping stroke, the gas used for such purpose is quickly relieved and introduced into the column of oil in the tubing above the apparatus whereby such column of oil is not only lightened but is also given added impetus in its upward movement through the tubing to the surface of the ground.

Other objects and advantages will appear from the following description and the drawing. In the drawing, which is for illustrative purposes only—

Fig. 1 is a sectional elevation of the pump and the pump operating assembly showing the parts in their relative positions at the end of the down-stroke;

Fig. 2 is a view similar to Fig. 1 showing the parts in the position assumed when the apparatus has reached the end of the upstroke;

Fig. 3 is a sectional plan view on line 3—3 of Fig. 1;

Fig. 4 is a sectional plan view on line 4—4 of Fig. 1; and

Fig. 5 is a fragmentary vertical sectional view on line 5—5 of Fig. 1.

In the embodiment of my invention shown in the drawing numeral 10 indicates the well casing having perforations 11 through which oil enters the well from the surrounding oil sands. Suspended by the tubing 13 which extends to the top of the well is what I have termed an outer tubular barrel 14. The lower end of this barrel 14 is provided with a head 15 into which is threaded or otherwise secured the upper end of a pump barrel 16. Oil may enter the lower end of this barrel through an opening 17, the passage of oil therethrough being controlled by a valve indicated at 18. 19 indicates a plunger movable

in the barrel 16, such plunger, as shown in Fig. 5, being threaded on the lower end of a hollow shaft or pump rod 20. This rod is provided with a valve seat indicated at 21 which receives a ball valve 22 thereon. The rod is slotted as indicated at 23 to permit oil which has passed through the valve 22 to be discharged into the barrel 16 above the plunger 19. The pump rod is coupled to a drive rod 24 which extends through a packing box 26 mounted in a head 27 secured in the lower end of an inner tubular barrel indicated at 30.

The upper end of the drive rod 24 is mounted upon a pair of arms 32 which are secured to and extend downwardly from a piston 34. Numeral 35 indicates a tube which is threaded into the piston 34, the lower end of the tube forming a valve seat to receive a valve member 36 at the lower end of a valve stem 37 which extends upwardly through the tube 35 and through an opening indicated at 39 in a plate 40 forming part of a cage generally indicated at 41.

This cage comprises the flat perforated upper plate 40 from which extend rods 42 to a lower plate indicated at 43, such lower plate 43 being also perforated as indicated at 44. 45 indicates a cross bar secured to the valve stem 37 which, when the apparatus is at the end of the down stroke, rests upon the upper plate 40. The upper end of the stem 37 extends through and is guided in the upper part 46 of an upper cage or open frame indicated at 47. Plate 43 is also provided with a central opening 48 to slidably receive and guide the tube 35.

Mounted on the valve stem 37 and having its lower end resting on the cross bar 45 is a light spring indicated at 50. The upper end of the tube 35 is provided with an ear or bracket 51 which may be welded or otherwise secured thereto. A tripping finger 53 is pivotally mounted on the bracket 51 and normally rests upon and is supported by a fixed collar 54 secured to the stem 37.

Mounted on the tube 35 and interposed between the bottom plate 43 and the upper face of the piston 34 is a heavy coil spring 56. The tube is provided with a series of perforations indicated at 57 immediately above the piston for a purpose hereinafter described.

The cage 41 is maintained in proper position within the inner tubular barrel in the following manner: the upper plate 40 of the cage abuts against lugs indicated at 58 which extend inwardly from the inner face of the inner barrel 30, and, as indicated at 59 bolts 60 extend through the inner and outer barrels having their inner ends below the bottom plate 43 of the cage 41 so that the cage is maintained in position between the lugs 58 and the inner ends of the bolts or screws 60.

The upper end of the inner barrel is provided

with a check valve generally indicated at 61 and consisting of a valve seat 62 and a ball 63 in a cage 64. The upper end of the outer barrel is provided with a fitting indicated at 65 which connects the upper end of such barrel with the tubing 13, the fitting being provided with a valve seat indicated at 66 and a ball valve indicated at 67.

Extending downwardly through the tubing 13 from above ground where any suitable means may be utilized for introducing gas under pressure, is a pipe 78. This pipe 78 is provided with a connecting pipe 71 which extends through the tubing and into the space between the inner and outer barrels 30 and 14 respectively. The portion of the space between the inner and outer barrels into which the gas pipe extends constitutes a passage which is indicated at 72 and is formed by longitudinal walls 73 and 73' (see Fig. 3) which extend between the inner and outer barrels. The gas passage is closed at the bottom by means of a plug or block 74.

At the lower end of the passage 72 an inlet port 75 is provided in the inner barrel so that gas under pressure from the passage 72 may enter the barrel below piston 34. The remainder of the space between the inner and outer barrels forms an oil passage, indicated at 76, which is in open communication with the pump barrel 16 and with the valve 61 at the juncture of the tubing 13 and the outer barrel.

The operation of the apparatus is as follows: When the parts are in their relative positions shown in Fig. 1, the pump plunger 19 is at the bottom of its stroke as is also the piston 34 and when in this position the fluid under pressure, which may be air or gas, moves the piston 34 upwardly in the inner barrel and by reason of such pressure also causes the valve 36 to remain closed during such upward movement. The piston 34 being connected to the pump by rod 24 moves the plunger 19 upwardly in the pump barrel 16. This produces a suction under the plunger, opens the valve 18 and draws oil into the barrel under the plunger from the bottom of the well, the valve 22 remaining closed on such up stroke. This set of conditions causes the oil above the plunger 19 to move upwardly and into the oil passage 76 between the inner and outer barrels, such moving body of oil causing the valve 61 to open and the oil to enter the tubing 13. During this upward movement of the piston and connected parts, the spring 56 is compressed and after a portion of the upward movement the spring 58 is compressed. As the plunger approaches the end of its upward movement, the trip 53 engages the lower face of the plate 40 of the cage 41 and by such contact is depressed, thereby moving the rod 31 downwardly through the medium of the collar 54, opening the valve into the position shown in Fig. 2, the other parts of the apparatus as shown in Fig. 2 being in their proper relative positions when the piston 34 has reached the upper end of its stroke.

The opening of the valve 36 releases the gas under the piston 34 and permits it to rapidly discharge through the tube 35 and upwardly through the valve 63 into the body of oil above such valve and through the valve 61 into the oil in the tube and mixing therewith not only lightens such oil but at the same time gives the oil in the tubing an added impetus on its upward movement therethrough.

During this upward movement of the gas a portion of such gas is also discharged through

the perforations 51 in the tube 35 above the piston 34 and any oil which may have collected at such portion of the apparatus will be blown upwardly with the gas as it passes into the tubing.

5 The parts having assumed the position shown in Fig. 2, and the pressure below the piston 34 having been relieved, the piston moves downwardly under the influence of the spring 56 and due to the fact that the valve 36 is open and the pressure on the opposite side of the valve being substantially the same and by virtue of the spring 58 being compressed and engaging the cross bar 45 on the rod 31, such valve 36 remains open until the piston has substantially reached the lower end of its stroke where the operations just described are repeated.

Although in the foregoing description it has been pointed out as a feature of the invention that the gas exhausted from the region below the piston is introduced into the column of pumped oil, it is contemplated that in some installations it may be desirable to exhaust such gas externally of the pumping apparatus so that it will not enter the column of pumped liquid. In order to meet this contingency, the well pumping apparatus is provided with a short nipple 78 extending between the inner and outer barrels providing a communicating port from the interior of the inner barrel above the piston to the exterior of the outer barrel. In the drawing this port has been shown closed by a plug 79. During operation of the pump operating assembly, if the plug 79 is removed, practically all of the exhaust gas will escape through this port to a point exterior of the outer barrel.

It is contemplated that various modifications and changes may be made in the structure without departing from the invention and in this connection it is within the scope of the invention 40 to utilize various types of oil well pumps in combination with the pump operating assembly in place of the particular type of pump shown and described for the purpose of illustration.

I claim as my invention:

45 1. In well pumping apparatus, a string of tubing extending into the well; a reciprocating plunger type pump; an outer barrel connected to the lower end of the string of tubing at its upper end and having its lower end in communication with the pump; an inner barrel in said outer barrel spaced apart therefrom; wall means extending longitudinally between the barrels forming a passageway for the flow of oil upwardly from the pump to the string of tubing and a passage for the flow of gas downwardly; a gas 50 operated motor in said inner barrel; a port in said inner barrel providing communication between the motor therein and the gas passage between said barrels; means for supplying gas under pressure to the gas passage; means adapted to connect said motor with the plunger of said pump; and means for exhausting the gas from said motor at a suitable point.

60 2. In well pumping apparatus, a string of tubing extending into the well; a reciprocating plunger type pump; an outer barrel connected to the lower end of the string of tubing at its upper end and having its lower end in communication with the pump; an inner barrel in said outer barrel spaced apart therefrom to form an oil 65 passage between the barrels; a piston in said inner barrel; means connecting said piston with the plunger of said pump; means for introducing gas under pressure into the lower end of said inner barrel below said piston; means yieldably

urging said piston downwardly; and means for permitting escape of gas from below said piston to communication with the pumped oil at a point above the pump when the piston approaches the limit of its upward stroke and during a substantial portion of the downward stroke of said piston.

3. In well pumping apparatus, a string of tubing extending into the well; a reciprocating plunger type pump; an outer barrel connected to the lower end of the string of tubing at its upper end and having its lower end in communication with the pump; an inner barrel in said outer barrel spaced apart therefrom to form an oil passage between the barrels; a piston in said inner barrel; means connecting said piston with the plunger of said pump; means for introducing gas under pressure into said inner barrel at one end of said piston; means yieldably urging said piston toward the end of said barrel into which the gas is introduced; and means for permitting escape of gas from said barrel to a desired point during a certain portion of the stroke of said piston.

4. In well pumping apparatus; a string of tubing extending into the well; a reciprocating plunger type pump; an outer barrel connected to the lower end of the string of tubing at its upper end and having its lower end in communication with the pump; an inner barrel in said outer barrel spaced apart therefrom to form an oil passage between the barrels; said inner barrel being closed at its lower end and being provided with an inwardly opening check valve at its upper end; a piston in said inner barrel; means connecting said piston with the plunger of said pump; means for introducing gas under pressure into the lower end of said inner barrel below said piston; means yieldably urging said piston downwardly; and means for permitting escape of gas from below said piston to the upper end of said barrel when the piston approaches the limit of its upward stroke and during a substantial portion of the downward stroke.

5. In a well pump operating means, the combination of: a barrel; a piston in said barrel; closure means for the lower end of said barrel; a rod extending through the closed end of the barrel; means yieldably urging said piston downwardly; means providing communication to opposite sides of said piston; a valve controlling said communication means and including a valve member having a valve stem extending upwardly from said piston; means for positively opening said valve when the piston reaches the upper limit of its stroke; a relatively light spring operable to hold said valve open during the major portion of its return stroke; and means for admitting fluid under pressure to the lower end of said barrel below said piston.

6. In a well pump operating means, the combination of: a barrel having an upwardly opening check valve in the upper part thereof and having closure means at its lower end; a piston in said barrel; an operating rod connected to

5 said piston and extending downwardly therefrom through the lower end of said barrel; a tube mounted on said piston, said tube forming a fluid passage for providing communication to opposite sides of said piston; a valve adapted to control said fluid passage including an upwardly extending valve stem; means in said barrel for limiting downward movement of said valve stem; means for yieldably resisting upward movement of said valve stem after said valve stem has moved a limited distance with said piston; an abutment on said valve stem; a pivotally mounted trigger on the upper end of said tube engageable with a stationary element in said barrel and with said abutment on said valve stem for opening said valve; means yieldably urging said piston downwardly; and means for admitting fluid under pressure into the lower end of said barrel below said piston.

10 7. In a well pump operating means, the combination of: a barrel; a piston in said barrel; closure means for the lower end of said barrel; a rod mounted on said piston and extending through said closure means; a tube mounted on said piston extending upwardly therefrom; a valve seat at the lower end of said tube; a valve normally seated on said valve seat; a valve stem extending upwardly from said valve; an open cage mounted in said barrel in fixed relation thereto having a part forming a guide for said tube; a pivoted member on said tube engageable with a part of the cage and with the valve stem to open the valve at a predetermined point in the stroke of said piston; yieldable means between the cage and the upper face of the piston; guide means for the upper end of the valve stem above the cage; a cross bar fixed to said valve stem normally resting on a part of said cage; a light spring on said stem seated on said cross bar adapted to engage said cage; and means for introducing gas under pressure into said barrel below said piston.

15 8. In a well pumping apparatus, a string of tubing extending into the well; a plunger type pump; an outer barrel connected to the lower end of the string of tubing at its upper end and having its lower end in communication with the pump; an upwardly opening check valve between said tubing and said outer barrel; an inner barrel in said outer barrel spaced apart therefrom; wall means extending longitudinally between the barrels forming a passageway for the flow of oil upwardly from the pump to the string of tubing and a passage for the flow of gas downwardly; means for supplying gas under pressure to the gas passage; a gas operated motor in said inner barrel; a port in said inner barrel providing communication between the motor therein and the gas passage between said barrels; means adapted to connect said motor with the plunger of said pump; and means for exhausting the gas from said motor at a suitable point.

WILSON E. GREEN.
